ONE-PIECE SOCKET

Daniel I. Reiter, New York, N. Y.

Application July 18, 1933, Serial No. 680,969

12 Claims. (Cl. 24—216)

This invention relates to snap fasteners and particularly, to snap fasteners made from one piece blanks.

My invention contemplates the provision of an inexpensive but efficient snap fastener comprising a one-piece socket adapted to be used in connection with comparatively stiff sheet material such as card-board, wood or the like.

My invention further contemplates the provision of a simple, inexpensive, one-piece resilient socket adapted to cooperate with a suitable stud and similarly formed of a flat blank and provided with resilient fingers.

The various objects of my invention will be clear from the description which follows and from the annexed drawing, in which,

Fig. 1 is a vertical section of my snap fastener including the stud and socket as they appear secured in place to comparatively stiff sheets of material.

Fig. 2 is a top plan view of the stud.

Fig. 3 is a bottom plan view of the stud.

Fig. 4 is a plan view of a blank from which the stud shown in Figs. 2 and 3 may be made.

Fig. 5 is a fragmentary plan view of a modified form of the blank from which a slightly modified form of stud may be made.

Fig. 6 is a vertical section of the socket shown in Fig. 1.

Fig. 7 is a bottom plan view of the socket.

Fig. 8 is a plan view of the blank from which the socket shown in Figs. 1, 6 and 7 is made.

In the practical embodiment of my invention which I have shown by way of example, and referring to Fig. 1, there is shown a one piece socket 10 and a one piece stud 11 in engagement. The socket and stud are secured, respectively, to sheets of material 12 and 13 which preferably are wood, card-board or other such hard or stiff material.

It will be understood, however, that the socket and stud may be used in connection with comparatively flexible material such as leather, textiles or the like. The stud 11 is preferably made from a flat blank such as is shown in Fig. 4 and is composed of integral parts suitably shaped to perform their intended functions. Said parts include the domed-shaped top portion 20, and a plurality of partly cylindrical side portions 21 depending from the top portion and having

edges 22 closely adjacent or in contact with each other.

Extending outwardly from the lower of said side portions is the annular doubled flange portion 23 consisting of the upper flange 24 and the lower flange 25. The upper flange as shown in

Figs. 2 and 4 is provided with a series of projections 26 alternately and cooperating with recesses 27 for the purpose of interlocking said projections and recesses and thereby securing a more rigid structure and preventing lateral distortion of the flange which might occur under stress of operation or during the tumbling operation and at other times. Below the doubled flange 23, there is a tubular portion 28 composed of a series of preferably abutting cylindrical members, the lower end portions of which are adapted to be bent outwardly to form the single flange portion 29. To assemble the stud with the sheet 13, the upper flange 23 is placed against the upper surface of the sheet and the lower flange 29 bent into firm contact with the lower surface of the sheet.

In Fig. 2, which is a plan view of the completed and attached stud, the dome-shaped portion 20 is visible and is also, the upper portion 24 of the flange 23. In this form of my invention, the alternate projections 26 are shown interlocked with the adjacent alternate recesses 27 to provide a rigid structure not easily distorted and forming a smooth and uninterrupted flange.

As shown in Fig. 5, the same result may be attained by making a pair of opposed projections 26' on each alternate radial arm of the blank; and making a corresponding pair of recesses 27' on the other alternate radial arms.

In Fig. 3, which is a bottom plan view of the stud, the single flange elements 29 are shown. It will be noted that the elements 29 of the blank as shown in Fig. 4 are the only parts of the stud elements which become separated when the stud is secured in place as shown in Fig. 3; that the side portions 28 of the stud, on the contrary, have their edges 30 preferably in contact to form an uninterrupted tube, as shown in Fig. 1; that the lower parts 25 of the doubled flange 23 likewise have their edges in contact, that the upper parts 24 including the edges of the projections 26 and the recess 27 likewise are in contact to form an uninterrupted and continuous wall when the blank, as shown in Fig. 4, is formed into its final shape as shown in Figs. 1 and 2, and also, that the side portions 21 of the upper part of the stud have their edges 22 in contact when the blank 4 is formed into the stud, as shown in Fig. 1 to form a continuous head.

The stud 11 accordingly is formed from a one-piece blank as shown in Figs. 4 and 5, and is bent to form integral parts, the edges of which are preferably in contact with each other with the exception of the bottom flange 29, which is employed to secure the stud to the sheet 13.

The respective series of contacting edges 22 and 30 of the stud 11 form slits as distinguished from open spaces which might be called slots. The projections 26 fit into the recess 27 and lend 5 rigidity to the stud 11.

In Figs. 1, 6, 7, and 8 is shown the socket 10 which cooperates with the stud 11 to form my complete snap fastener. Referring to Figs. 1 and 6, the one-piece closed or capped socket 10 is formed from a suitable blank such as the flat blank shown in Fig. 7 in a manner similar to the formation of the stud. The blank is bent to form integral parts including a dome-shaped head 40 to receive and conceal the stud head 10 and having outwardly convex side portions 41. The side portions 41 have their edges 42 in contact with each other to form slits and to provide a smooth, uninterrupted surface on the resilient socket. Below the side portions 41, 20 there is a comparatively narrow tubular portion consisting of the tubular elements 43, the edges 44 of which are also preferably in contact with each other. To form the securing flange 45, the lower portions of the alternate elements 43 are bent radially outwardly and thereby become 25 spaced from each other.

Integral with the socket are the resilient fingers 46, which are bent within the tubular portion of the socket from the end portions of 30 those elements 43 which are between the elements from which the flange 45 is bent. Said fingers are thereby spaced from each other and also are spaced inwardly from the remainders of the tubular elements 43 to permit a resilient 35 engagement with the head of the stud 11. The securing flange 45 and the bulging side portions 41 of the socket 10 are adapted to receive the sheet 12 between them, the alternate elements 43 being passed through a suitable perforation 40 in the sheet and flanged over on the lower surface of the sheet, thus to secure the socket to the sheet.

It will be noted that the socket 10 is formed from a one piece blank as shown in Fig. 8 which is made with a plurality of radial arms alternating 45 to form the flanges 45 and the resilient fingers 46.

The flange extensions are therefore preferably made longer than the resilient finger extensions. 50 When the socket 10 is formed, the edges of the dome portion as well as the edges of tubular elements preferably contact with each other to form a continuous surface.

Both the stud 11 and the socket 10 are simple 55 in construction and inexpensive to manufacture. They form an economical snap fastener well adapted for inexpensive use as in pencil boxes or cases and the like. They are rigid and not likely to become distorted and otherwise meet 60 the severe requirements of practical use.

While I have shown and described certain 65 specific embodiments of my invention, it will be understood that I do not intend to limit myself to these embodiments, but that my intention is to claim my invention as broadly as is permitted by the scope of the appended claims and the state of the prior art.

I claim:

1. A one-piece snap fastener socket bent from a 70 flat blank, said socket having a head provided with convex side portions having their edges in contact with each other, a tubular portion of separate members depending from and continuous with said side portions, the lower end 75 parts of alternate members when bent outward-

ly and radially from the positions assumed thereby in the tubular portion separating from each other and forming a flange adapted to engage the under surface of a sheet of material to aid in securing the element to said sheet, and resilient fingers bent inwardly and upwardly from the lower ends of the remaining members. 5

2. A one piece socket element having an imperforate top and having depending separate side portions arranged with their edges in contact to form a smooth, uninterrupted outer surface on the socket element, and resilient fingers formed from the end parts of alternate side portions and adapted to engage a stud element, the remaining side portions being bent outwardly to form a discontinuous attaching flange. 15

3. A one piece socket element having depending separate side portions arranged in edge adjacent relation to form a smooth outer surface on the socket element and to form a tube, and resilient fingers formed from the end parts of alternate side portions and adapted to engage a stud element, the end parts of the remaining side portions when bent outwardly forming an 20 attaching flange. 25

4. A one piece socket element provided with a head and with a tubular portion depending from the head and comprising separate parts, each free at the outermost end thereof, and resilient stud-engaging elements bent out of the 30 tubular portion from the free end portions of the alternate parts of said tubular portion, the free ends of the remaining parts when bent outwardly out of the tube, forming an attaching 35 flange for the socket.

5. A one piece socket bent from a flat blank to form integral parts including a dome-shaped head, said head having convex side portions arranged with their edges in contact with each other, a narrowed tubular portion of separate 40 members continuous with said side portions having their edges in contact with each other, the lower parts of alternate members being adapted to be bent normal to and outwardly of the remainder of said tubular portion, and integral 45 resilient fingers bent inwardly and upwardly from the lower ends of the remaining members.

6. A one piece socket provided with separate members terminating at their upper ends in an integral connecting portion and arranged with 50 their edges in contact to form a tubular portion at the lower part of said socket, the lower ends of alternate members being bent inwardly and upwardly to provide resilient fingers, and the lower ends of the remaining members being 55 adapted to be bent outwardly to form a discontinuous flange.

7. A one piece socket bent from a flat blank having a central portion and arms radiating from the central portion, the alternate arms of the blank being longer than the remaining arms, said socket having a head comprising said central portion and having a tubular portion depending from the head and comprising parts of said arms intermediate the ends thereof, said socket 65 having resilient fingers bent from the lower end portions of the shorter arms, the lower ends of the remaining arms being arranged in tubular formation to provide an attaching flange for the socket when said lower ends of the remaining arms are bent outwardly. 70

8. A one piece socket bent from a flat blank having a central portion and arms radiating from the central portion, the alternate arms being longer than the remaining arms, said socket 75

comprising a dome-shaped convex head, the top of said head comprising said central portion and the side portions of the head comprising the inner parts of said arms, said side portions 5 being arranged in edge-abutting relation to form an uninterrupted outer surface on the head, the lower part of said head being shaped to engage one face of a sheet of material, a tubular portion depending from the head and comprising members continuous with said side portions and arranged in edge-abutting relation to form an uninterrupted surface on said tubular portion and resilient fingers bent inwardly from the lower ends of the shorter arms, the remaining longer 10 arms being adapted to be bent outwardly at their lower ends to form a discontinuous flange.

9. A one piece socket formed of a single flat blank and provided with an enlarged head, a tubular portion depending from the head and 15 comprising a series of adjacent side portions, alternate side portions being longer than the remaining side portions, resilient stud-engaging fingers bent from said alternate side portions, the lower parts of said remaining side portions projecting downwardly beyond said fingers and being arranged in the form of a discontinuous cylindrical tube, said lower parts when bent outwardly forming an interrupted attaching flange for the socket.

30 10. A one piece socket bent from a flat blank to form integral parts including a head, said head having a series of separate side portions arranged to form a side surface on the head, a narrowed tubular portion of separate members

continuous with said side portions, the lower parts of alternate members being bent normal to and outwardly of the remainder of said tubular portion to form a discontinuous attaching flange, and integral resilient fingers bent from the lower ends of the remaining members into position to engage a cooperating stud. 5

11. A one piece resilient socket comprising an imperforate head, said head having a side portion comprising a series of separate side-forming members, a tubular portion of less diameter than the side portion and comprising separate tube-forming members continuous with the respective side forming members, the lower parts of alternate tube forming members when bent 15 outwardly of the remainder of said tubular portion forming a discontinuous attaching flange, and integral resilient fingers bent from the lower ends of the remaining tube forming members and adapted to engage a cooperating stud for snapping engagement and disengagement with said stud. 10

12. A one piece socket element of sheet metal having separate side portions arranged in edge adjacent relation and in the general form of a tube, and resilient fingers bent out of the tube from the end parts of a selected number of said side portions and adapted to engage a stud element, leaving at least two of said side portions 25 in the tube between said fingers, the end parts of the remaining side portions between said fingers when bent outwardly forming an attaching flange. 30
